[57] CLAIM

The ornamental design for a cigarette lighter adapter, as shown and described.

DESCRIPTION

FIG. 1 is a rear, bottom, and right side perspective view of

a first embodiment of a cigarette lighter adapter;

FIG. 2 is a top plan view of the first embodiment;

FIG. 3 is a right side elevation view of the first embodiment;

FIG. 4 is a front elevation view of the first embodiment;

FIG. 5 is a left side elevation view of the first embodiment;

FIG. 6 is a bottom plan view of the first embodiment;

FIG. 7 is a rear elevation view of the first embodiment;

FIG. 8 is a rear, bottom, and right side perspective view of a second embodiment of a cigarette lighter adapter;

FIG. 9 is a top plan view of the second embodiment;

FIG. 10 is a right side elevation view of the second embodiment;

FIG. 11 is a front elevation view of the second embodiment;

FIG. 12 is a left side elevation view of the second embodiment;

FIG. 13 is a bottom plan view of the second embodiment; and,

FIG. 14 is a rear elevation view of the second embodiment.

The broken line matter in all figures is for illustrative purposes only and forms no part of the claimed design.
